[57] CLAIM

The ornamental design for a deep-sea fisherman's chair, as shown and described.

DESCRIPTION

FIG. 1 is a perspective view of my new deep-sea fisherman's chair;

FIG. 2 is a side elevational view thereof;

FIG. 3 is a front elevational view thereof;

FIG. 4 is a rear elevational view thereof;

FIG. 5 is a top plan view thereof; and,

FIG. 6 is a bottom plan view thereof.

A side elevational view taken from the side opposite that shown in FIG. 2 is essentially a mirror image thereof.
